WORK HOLDER

John E. McPhee and Jack H. B. Herts, Grand Rapids, Mich., assignors to John Widdicombe Company, Grand Rapids, Mich., a corporation of Michigan

Application March 21, 1949, Serial No. 82,551

5 Claims. (Cl. 91—60)

1

This invention relates to a jig for carrying and holding flat parts such as head and foot boards of beds, and supporting them in positions where they may be carried through a finishing process on supporting pallets, to which the jigs or fixtures are detachably secured.

It is an object and purpose of this invention to provide a readily removable jig which may be attached to standard finishing pallets to accommodate head and foot boards of any of the sizes of beds, and hold and retain them within the outlines of the pallets in position such that any or all the finishing operations to be performed may take place on head and foot boards, without removal from the carrying jigs or any change of position thereon.

It is a further object and purpose to provide a jig of the type noted on which a head or foot board, either one or both, or a plurality of them may be carried, all surfaces requiring finishing being readily reached by a spray gun and no defects left to mar exposed surfaces. Furthermore such jigs are of simple, sturdy and economical character and are readily produced for the purposes for which they are to be used.

An understanding of the invention may be had from the following description, taken in connection with the accompanying drawings, in which,

Fig. 1 is a side elevation showing the mounting of a jig on a pallet, the pallet being shown in end view.

Fig. 2 is a perspective view of one of the head and foot board holding members, a plurality of which are used in practice with each jig.

Fig. 3 is a transverse section, enlarged, on the plane of line 3—3 of Fig. 1.

Fig. 4 is a perspective view showing two of the jigs detachably mounted on a pallet and spaced from each other, as they are used, and

Fig. 5 is an enlarged, generally vertical section, substantially on the plane of line 5—5 of Fig. 3.

Like reference characters refer to like parts in the different figures of the drawings.

A standard pallet 1 of generally rectangular outline, and which is horizontally located when in use, may have at its opposite longitudinal edges notches or recesses therein for the location of the jigs which are to be detachably secured. As many of such notches or recesses in pairs, as may be wanted will be provided in such longitudinal edges. In the structure shown in Fig. 4, two pairs of the notches or recesses, one adjacent each end of the pallet at which the jigs are detachably secured are shown.

Each of the jigs include a flat horizontal lower bar 2 of metal which, at what may be termed its rear end, is bent downwardly, as at 3, and terminates in a forwardly extending lip to provide a hook to seat in a rear recess at the back edge of the pallet. At the front edge of the pallet a gen-

2

erally vertical jaw member 4 has, at its lower end, a lip 5 turned to the rear for engagement with the pallet at the forward notch or recess of the pair of notches in which the rear hook 3 of the bar 2 is located. Such member 4 is pivotally connected above the pallet, at 6, to a vertically extended member 7 integral with and at the front end of the bar 2. The member 4 through its pivotal connection at 6 may be manually actuated to release the jig when wanted. The pivoted member 4 is acted upon by a spring, shown partly in Fig. 1, to normally swing the lower part of the jaw into pallet engaging position.

An elongated bar 8 extends upwardly and to the rear from the front end portion of the horizontal bar 2. A second shorter bar 9 extends from the rear end portion of the bar 2 toward the bar 8, engaging it substantially midway between the ends of the bar 8, and is permanently secured thereto by welding or other suitable means. The bars 8 and 9, at their lower ends, are connected with the bar 2 by welding or otherwise and are reinforced by plates 10 as shown.

The bars 8 and 9 are of a generally channel form in cross section, each having a web 11, and two spaced parallel flanges 12 extending therefrom, each of which terminates in an inwardly turned elongated lip 13 (Fig. 3). The bars 8 and 9 when the jig is on a pallet, have the webs 11 preferably located at their inner sides as shown in Fig. 4.

On each of the channel bars 8 and 9 a number of fixtures are mounted for adjustment to different positions. Each is made from a plate of metal 14 which at one end has an inturned tongue 15. The tongue 15 near its juncture with the plate 14 is recessed at opposed edges, as at 16. Also said tongue 15 at opposite edges is beveled as best shown in Fig. 5.

At the opposite end of the plate 14, a narrow width of metal is turned at right angles in the same direction as tongue 15, providing an arm 17 which terminates in an extension 18 at right angles thereto (Fig. 2). Such fixture 14 or a number of them, may be mounted upon bar 8 or 9 by inserting the tongues 15 in the slots between the adjacent edges of the lips 13, a fixture occupying substantially the position shown in dash lines in Fig. 5, and after the tongue has been inserted, turning it to the full line position, whereupon the lips 13 extend into the recess at 16 and the sharpened edges at opposite side edges of the tongue 15 bite into the flanges 12 at the inner sides thereof, to hold the fixture at any position selected in the length of a bar 8 or 9 on which it is mounted. When turned to the full line position, in Fig. 5, the arm 17 extends across the upper flange 12 of the bar to which attached, with the terminal section 18 extending downwardly at the inner side of the web 11.

The plate 14 of the fixture, substantially mid-

way between its ends and at its outer edge, has a narrowed portion 19 which, at its end and at one side edge, is provided with a pointed or wedge shaped projection 20. Spaced a short distance from said projection 20, and below it, is a hump at 21, and at the end of the fixture 14 nearest the arm 17 another raised hump 22 is provided as shown.

In Fig. 1, in dash lines, a plurality of foot boards are shown carried at the front of the bars 8 of two spaced jigs which are detachably mounted on the pallet, with the foot boards between two of the adjustable carrying fixtures 14 thereon on each bar 8. The lower ends of the legs of a foot board are engaged against and may be slightly penetrated by the pointed wedges or tangs 20 and rest against the humps at 21 of the lowermost fixtures, while at the upper end of the foot board it rests against the humps 22 of the next uppermost fixtures 14. A succession of the foot boards 23 may be mounted in this manner between the lower and upper parts of the bars 8 of the jigs; and it is of course evident that by increasing the distance between the holding fixtures 14, they may be adapted for similarly carrying a head board or a number of them.

In the same manner foot or head boards may be carried at the back of the two jigs on the bars 9. In such positions whether head boards or foot boards, all areas thereof requiring finish may be reached by a spray gun. Normally only one side of a head board may be finished and nothing will come in contact with such finished surface to mar it. If a foot board is finished on both sides, the only points of contact may be that one of the sides after finishing may be engaged against the humps 22 and 21, but marring under such conditions of foot boards of light weight does not take place. The penetration of the projections 20 at the lower ends of the legs of a foot or head board is not of importance as it is not seen and does no damage.

The structure is practical and very useful. The holding jigs may be readily attached to and detached from a pallet 1. Pallets of the type disclosed may be moved on a factory line in a factory from one place to another as for example, from a finishing station to a drying oven, after the finish has been sprayed upon the head and foot boards, so that handling the manufactured parts is reduced to a minimum with resultant saving.

The invention is defined in the appended claims and is to be considered comprehensive of all forms of structure coming within their scope.

We claim:

1. In a structure as described, a horizontal pallet, a plurality of spaced jigs located above and detachably connected with said pallet, each jig including a horizontal bar bearing against the upper side and bearing transversely of the pallet, an upwardly and rearwardly inclined bar permanently secured at the front end of said horizontal bar, a second inclined bar mounted near the rear end of said horizontal bar and extending upwardly and forwardly to the first inclined bar and having permanent connection therewith between its ends, and a plurality of fixtures adjustably mounted for lengthwise adjustment of each of said inclined bars, each having on its forward portion an upwardly extending prong and below it a forward extension for holding a head or foot board of a bed thereon on two lower fixtures mounted on like inclined bars of the spaced apart jigs, and resting against the two fixtures

next above the lower fixtures, as and for the purposes described.

2. A jig adapted to be secured to a horizontal pallet comprising, a lower horizontal bar having a downwardly turned hook portion at one end and an upwardly extending member at its other end, a second member pivotally connected to the first mentioned member at a point above said horizontal bar, said second member having a downwardly extending jaw portion, said jaw portion and said hook at the opposite end of the horizontal bar being adapted to engage at opposed longitudinal edges of a pallet for connection of the horizontal bar thereto, two upwardly inclined bars permanently connected, one adjacent each end of the horizontal bar, inclined upward toward each other to meet each other, and permanently connected together at the point of meeting of said inclined bars, and a plurality of head or foot board securing and carrying fixtures adjustably mounted on said inclined bars each having on its forward portion an upwardly extending prong and below it a forward extension and adapted to be spaced from each other at pre-selected positions in the length of said inclined bars.

3. A structure as defined in claim 1, said inclined bars being of channel form in cross section, the free-edge portions of the flanges of said channels terminating in lips extending toward each other lengthwise of each bar, each of said bars having an opening extending the length thereof between said lips, and said fixtures each comprising a plate of flat metal having a tongue at one end extending at right angles therefrom for passage through said elongated opening between said lips for engaging the flanges of a bar at the inner sides thereof.

4. A structure as defined in claim 3, said plate of each fixture at the end thereof opposite said tongue having an outwardly extending raised hump, and a second hump above and spaced from and located inwardly from said pointed projection.

5. In a structure as described, a horizontal pallet, a pair of spaced jigs located above said pallet and spaced apart thereon, said jigs being in substantially parallel vertical planes, each jig including a lower horizontal bar at the upper side and positioned across and bearing against said pallet, means at the ends of the bar for connecting it to a pallet, two upwardly inclined bars one permanently secured at its lower end near the front end of the horizontal bar and the other at its lower end near the rear end of said horizontal bar, said inclined bars converging and meeting each other and having permanent connection at their points of meeting, and a plurality of head and foot board holding and carrying members adjustably mounted on each of the inclined bars of both jigs for selective spacing of said holding and carrying members at predetermined portions and distances from each other on said bars, each carrying member having on its forward portion an upwardly extending prong and below it a forward extension.
